UNITED STATES PATENT OFFICE.

CARL O. BORKMAN, OF VICTOR, COLORADO.

WRENCH.

Application filed September 1, 1921. Serial No. 497,562.

To all whom it may concern:

Be it known that I, CARL O. BORKMAN, a citizen of the United States, residing at Victor, in the county of Teller and State of Colorado, have invented certain new and useful Improvements in Wrenches; and I do declare the following to be a full, clear, and exact description of the invention, such as will enable others skilled in the art to which it appertains to make and use the same.

This invention relates to an improved wrench of the quick-adjustable type which can be advantageously used upon pipes.

The principal object of the invention is to generally improve upon wrenches of this class by producing one of extreme simplicity and durability, which is such in construction that it can be quickly adjusted to fit various diameters of pipes with one hand.

Another and very important object of the invention is to provide a wrench embodying the usual handle and fixed jaw, together with a freely movable jaw slidably mounted on the handle and held in various set positions by novel mechanism which embodies a locking lever or catch carrying a spring which exerts tension against the movable jaw to maintain the latter in various positions in which it is placed by hand previous to engaging it with the work, after which it functions to hold the movable jaw in engagement with the work, and has the additional function of automatically moving the locking lever to operative position when taking a new grip.

A further object of the invention is to provide a wrench of the foregoing construction, the movable jaw being so shaped and connected with the slidable carrier that it automatically obtains a more effective grip on the pipe when the handle is moved in the direction for turning the latter, this particular shape being also advantageous in that it enables the wrench to be quickly and easily disengaged from the work.

A still further object of the invention is to devise a wrench of the type set forth above, wherein the parts are so arranged that the aforesaid spring coacts with the movable jaw in a manner to move said jaw away from the work when the lever is depressed by the finger, whereby to facilitate

disengagement of the wrench from the work.

Other objects and advantages of the invention will be apparent during the course of the following description.

In the accompanying drawings forming a part of this specification and in which like numerals are employed to designate like parts throughout the same:

Figure 1 is a side elevational view, with a portion of the carrier removed, showing the parts in their normal position.

Figure 2 is an edge elevational view of the improved wrench.

Figure 3 is a view like Fig. 1 showing the position of the parts at the time the wrench is engaged with a piece of pipe.

Figure 4 is a transverse sectional view taken substantially on the plane of the line 4-4 of Fig. 1.

Referring to the drawings by numerals, 1 designates a handle which is equipped at its outer end with a laterally disposed fixed jaw 2. Slidably mounted on this handle is a substantially U-shaped carrier 3, between the side portions of which, a movable substantially arcuate toothed jaw 4 is pivotally connected at one end as indicated at 5. It is to be noted here that the inner edge portion of this jaw is rounded as indicated at 6 to serve a purpose to be hereinafter described. Also disposed between and pivoted to the side portions of the carrier 3 is a locking lever 7 which is fulcrumed between its ends as indicated at 8. Along its inner edge, this lever 7 is equipped with a tooth or projection 9 which is designed to be received in one of the depressions 10 formed along the inner edge of the handle. Anchored at one of its ends to the intermediate portion of the lever 7 is a comparatively strong flat spring 11 which is of such a length that the free end of one of the arms thereof bears against the curved inner end or surface 6 of the movable jaw 4. Note should be made of the fact that the point of engagement of the spring arm just mentioned, is inward of the pivot pin, that is in rear of said pin. Hence, as before indicated, the spring serves four important points. First, it maintains the jaw in engagement with the work. Second, it holds

this jaw in any set position to which it has been moved by hand prior to engagement with the work. Third, it renders the co-acting means between the lever and handle effective until released by hand. Last, but not least, it serves to swing the jaw away from the work, whereby to facilitate disengagement of the wrench from the work, this outward movement of the jaw taking place 10 when the lever is depressed to permit sliding movement of the guide. It is also to be stated here that by an arcuate jaw in the manner shown, the latter is permitted to swing on its pivot so that it can be swung 15 outwardly a considerable distance to enable the innermost or intermediate teeth to be engaged with the pipe. Furthermore, it is yet to be pointed out that a pin 12 is passed transversely through the side portions of 20 the carrier 3 to limit the canting of this part of the device, this pin bearing against the inner edge of the handle as shown.

The operation of the improved wrench is as follows: Assuming that it is desired to 25 move the jaws comparatively close together for engaging them with a rather small pipe, it will be seen that it is only necessary to place the thumb against the upper end of the lever 7 as indicated in Figure 3 and to 30 push inwardly. Such action lifts the toothed projection 9 out of the depression in which it is then seated and the carrier can be slid along the handle to place the movable jaw 4 at the desired point. To 35 obtain the initial grip on the pipe, the movable jaw 4 is manually forced into engagement with the pipe and the spring 11 which exerts a tension against same, serves to hold it in the position to which it has been 40 moved. To turn the pipe it is only necessary to move the handle in the direction of the arrow A. Due to the peculiar shape of the movable jaw, it will be seen that such movement of the handle will cause the jaw 45 to obtain a tighter and more effective grip on the pipe as it is moved in this direction. When moving the handle in an opposite direction, the jaw 4 will become automatically disengaged from the pipe and the 50 spring 11 will maintain the latter in a position to grip the pipe again when the handle is moved in the direction first named.

By carefully considering the description in connection with the drawings, persons 55 familiar with devices of this class will doubtless be able to obtain a clear understanding of the invention. Therefore, a more lengthy and detailed description is deemed unnecessary.

60 Since probably the best results may be obtained with the construction and arrangement herein shown and described, this is taken as the preferred embodiment of the invention. However, I wish it to be understood 65 that minor changes coming within

the scope of the subjoined claims may be resorted to if desired.

I claim:

1. A wrench comprising a handle having a laterally disposed fixed jaw at its outer end, a carrier slidably mounted on said handle, a movable jaw pivotally connected at its inner end to said carrier, a locking pawl or lever fulcrumed between its ends on said carrier, co-acting means between the lever and handle for holding the carrier in various adjusted positions, and unitary means carried entirely by said lever and operatively engaged with the movable jaw for maintaining the latter in various positions prior to engaging it with the work, for holding it in engagement with the work, for rendering the aforesaid co-acting means effective, and for swinging the jaw away from the work when the outer end of the lever is pressed toward the handle to render the aforesaid co-acting means ineffective. 75

2. A wrench comprising a handle having a laterally disposed fixed jaw at its outer end, a carrier slidably mounted on said handle, a movable jaw pivotally connected at its inner end to said carrier, the inner end of said jaw being rounded or curved, a locking pawl or lever fulcrumed between the ends on said carrier, coacting means between the lever and handle for holding the carrier in various adjusted positions, and a flat spring connected in the intermediate part of said lever and bearing at its free end on the curved or rounded inner end of the pawl inward of the pivot point of the latter, said spring serving to maintain the jaw in various positions to hold it in engagement with the work to render the aforesaid coacting means effective 100 and serving to swing the jaw away from the work when the lever is pressed to render the aforesaid coacting means ineffective. 105

3. A wrench of the class described comprising a handle having a laterally disposed stationary jaw at its outer end and being provided along its inner edge with a plurality of closely spaced depressions, a substantially U-shaped carrier having its side portions disposed on opposite sides of said handle, a pin passing through the side portions of the carrier and engageable with the inner edge of said handle for limiting the degree of canting of the carrier, a substantially arcuate toothed jaw pivoted at one end between the side portions of said carrier adjacent the upper corners thereof, the inner pivoted end of said jaw being rounded or curved, a manually actuated locking lever fulcrumed between its ends on the side portions of said carrier adjacent the lower corners of said side portions, the edge of said lever adjacent the inner edge of the aforesaid handle being flattened to extend 110 115 120 125 130

in substantial parallelism with said handle and being equipped with a lug or projection designed for reception in one of the aforesaid depressions, and a flat spring secured 5 to said lever intermediate the ends of the latter, the free end of said spring bearing against the curved inner end of said mov-

able jaw for maintaining the latter in various set positions, and for holding said lug in said depression.

In testimony whereof I have hereunto set my hand.

CARL O. BORKMAN.
